UNITED STATES PATENT OFFICE

CHARLES B. PALMER AND KRISTIAN KRONBORG, OF MIDDLETOWN, OHIO, ASSIGNEES
TO THE AMERICAN ROLLING MILL COMPANY, OF MIDDLETOWN, OHIO, A CORPORATION OF OHIO

CONTINUOUS PICKLING MACHINE

Application filed November 9, 1926. Serial No. 147,311.

Our invention relates to continuous pickling machines of a type wherein the objects to be pickled are carried through a tank of pickle liquor on hangers depending from 5 conveyor means, without immersing the conveyor means in the pickle liquor.

It is the object of our invention to provide a continuous pickler of the general type noted, for high speed and low speed operation 10 as applied to the object carriers, for the purpose of permitting the carriers to move slowly in close relation to each other through a pickling tank, and move rapidly in spaced relation throughout the remainder of the 15 mechanism, so as to greatly increase the capacity of a machine and tank of given size, and at the same time permit of loading and unloading the sheets from the conveyor, either automatically or manually.

20 It is our object to provide for a novel carrier for sheet metal which will be suitable for use with our machine, and to provide a novel sheet unloading device for use with the said carriers.

25 We accomplish our objects by that certain construction and arrangement of parts to be hereinafter more specifically pointed out and claimed.

In the drawings:—

30 Figure 1 is a section taken through the top of the rapid conveyor system, showing the carrier device in detail.

Figure 2 is a cross section showing the carrier device.

35 Figure 3 is a detail of the rapid conveyor chain.

Figure 4 is a side elevation of one of the hook plates.

40 Figure 5 is a detail of the slow conveyor chain.

Figure 6 is a plan view of the conveyor chain of Figure 5.

Figure 7 is a side elevation of the machine, 45 on small scale, showing the general lay out of the device.

Figure 8 is a section on the line 8—8 of Figure 7.

Figure 9 is a section on the line 9—9 of 50 Figure 7.

Figure 10 is a section on the line 10—10 of Figure 7.

Figure 10^a is a section of the line 10^a—10^a in Figure 7.

Figure 11 is an isometric perspective illustrating the operation of the take off device. 55

The machine is naturally, where used for the pickling of sheet metal, a very large device, having a structural framework, cross members and bracket of structural steel, and no effort has been made to show fully all of the framework, and mounting devices of the various parts in any detail, other than what is believed necessary for an understanding of the operation of the invention. 60

The conveyor system, while it is merely the preferred of a number of possible forms, is the simplest which we have devised. The rapid conveyor has a pair of chains with spaced notched plates, in which the rod ends of the carriers are held, and the carriers ride on rails with flanged wheels, so that when the notched plates of the conveyor are not faced upright so that the carrier is held in place by gravity, the rails for the carrier, face the support for the conveyor chains, so that the chains hold the carriers against their rails and force them along. 70

The slow conveyor chains are similar to the rapid chains, but have closely spaced openings in which the rod ends of the carriers rest, and these chains are wider apart than the rapid chains, with the result that the rapid chains can deliver the carriers to the slow chains, and lift them away therefrom. 80

The rails that support the carriers thus lie outside of the path traversed by the carriers, except at the top of the machine, and the slow and rapid conveyor devices are timed so that a carrier will be delivered from one to the other without leaving any unfilled spaces. 85

Referring first to the framework, the same is generally indicated by the standards 1, and lengthwise bars 2, and braces 3. The tank is indicated at 4, the top edges thereof serving to support the guiding rails, and sprocket bearings for the slow conveyor. Guide rails for the carriers start near the front of the machine at 5, extend down where they lie along the top of the edges of the tank, and thence 90

extend along the tank at 5^a when they turn up again at 5^b at the delivery and return end of the tank. Along the top of the frame, the rails are indicated at 5^c. The vertical track portions and top horizontal portions overlap.

The conveyor chains of the rapid moving conveyor are carried on a pair of rails which extend along the top of the frame work as at 7, thence down paralleling, but spaced from the rails at 5 in the portion 7^a. The slow conveyor rails then begin and extend along the top of the tank edge as indicated at 7^b, and then stop where the carrier rails turn up at 5^a. The rapid conveyor rails extend up and along above the tank at 7^c, and return upwardly at 7^d, after being brought downwardly to a point adjacent the end of the slow conveyor.

The sprockets for the rapid conveyor chain are indicated at 8, 9, 10, 11, 12, 13, 14 and 14^a. The sprocket 10 may be mounted in slotted bearings 15, whereby slack in the chain may be taken up.

The sprockets for the slow conveyor are shown at 16 and 17.

Referring next to the carriers, which are shown in Figures 1 and 2, it will be noted that the several rails 17—17 and 5^c are located on the frame, at each side, by means of mounting brackets 18, secured in the frame in some suitable way. The carriers are formed of a main cross bar, in this instance a channel bar 19, to which are secured a series of plates 20, which extend away from the base of the channel at a downward slant. Mounted across the carrier by means of these plates is another cross member 21, in this instance a channel turned with the hollow face upwardly. A series of rods 22, having hook ends 23, with turned up tips 24, are secured in the channel bar 21, by means of looping the ends of the rods as at 25 through the bar, and clamping the rods to the flange of the bar by means of pieces 26, also 26^a.

Secured in the ends of the channel bar 19 are plates 27 in which are arranged the projecting rods 28. On the inner ends of the rods are suitable bearings for flanged wheels 29, by means of which the carrier rides on its supporting and guiding rails.

It may be observed that the several conveyor chains are equipped with means for engaging and actuating the carriers by means of elements which engage the rod ends of the carriers. This permits the carriers to rock on their supporting and engaging devices, so as to assume a position consistent with their center of gravity. The result of this is that the rods of the carriers will always maintain a position such as is shown in Figure 2, when the carriers are empty, thus facilitating mounting sheets in the carriers by upsetting them onto the hooked ends of the rods. When a sheet is held on the rods, the weight of the parts and the nature of the overhang of the

support of the rods, is so calculated that it will still preserve the sheet in a slightly angled position, so that it cannot tip off forwardly and fall from the carriers. This relation is maintained even in the liquor pickling bath, since the movement is not fast, and the several carriers are closely banked with relation to each other. Thus in the tank the friction of the pickle liquor against the sheets is not detracted from because of their slanting with the force of the stream against them.

The slow conveyor chains are formed with flanged wheels 30, 30, connected by pins 31, on which pins are mounted the twin plates 32, 32, in alternate close and spaced relation, so that the bodies of the plates form the links of the chain. The rail portions 7^b are arranged to support the slow conveyor chain flanged wheels, being mounted along each side wall of the tank as indicated in Figure 9.

The plates are formed with triangular bodies forming shoulders 33, and the rod ends of the carrier lie between the plates abutting the shoulders, and thus are fed along. When the machine is running in timed relation, there should be a carrier between each chain plate.

The rapid conveyor chain is best shown in Figures 3 and 4, in which there are a series of plain links 34, connected by pins, and spaced apart by the plain links are the special carrier links. Thus the carrier links are formed of pairs of spaced plates 35, held to the adjoining links by pins 36, which carry the flanged wheels 37, by means of which the chain is supported. The plates are formed of triangular shape with the notch 38 therein, of which notch the wall 39 is higher than the wall 40.

The rod ends of the carriers lie in the notches 38 of the plates, and when the conveyor chains are inverted as in their passage across the tank in the lower reach of their movement, the carrier rods can drop out of the notches to be picked up by the slow conveyor chains, and also the notch walls 39 may thrust down between rod ends of the carriers, where the carrier rails turn upwardly at 5^b.

At the receiving end of the machine we have indicated a loading platform 41, where workmen stand, and place sheets on the carrier rods, one sheet to each carrier. This task can also be performed mechanically by any device which will select a sheet from a pile, push it against the rods, and then tip off the rear end so as to lay it upright against the rods with the lower edges in the hooks.

Referring in detail to the delivery device, we have indicated in Figure 11, and in Figures 10 and 7, a series of conveyor belts 42, forming a table of interspaced moving elements. The belts are mounted on rolls 43, and move in the direction of the arrows, a transverse conveyor belt at 44, receiving the sheets, which are pitched outwardly and up.

wardly by the belts 42^a, so as to fall flat on the belt 44.

The spacing of the belts 42 is such as to pick the sheets off of the carriers. It will be noted that the guides at the delivery end of the machine are formed so that the carriers will pass up from the tank, thence in a downward sloping direction, and then up again to be returned for reloading.

10 During the downward sloping path of the carriers in this end of the machine, the edges of the sheets will strike against the belts 42 after they pass over the innermost rollers, and hence will be forced up, so as to be lifted from the protection of the tips of the hooks. The feeding action of the belts against the lower edges of the sheets will then act to draw the sheets away from the carriers and feed them flat and sidewise until they are 20 projected against the belt 44 and are fed to a drying oven or whatever subsequent process is called for.

As so constructed the operation of the machine is as follows: First referring to the 25 empty carriers, it will be noted that they are carried along in widely spaced relation by the rapidly driven conveyor chains at the top of the machine. When they reach the turn where the rails begin at 5, the chains 30 will become inverted and will press the flange wheels of the carriers against the rail portions 5, thus feeding the carriers in spaced relation down the path where they are loaded by workmen, each carrier with one sheet.

When loaded, the carriers pass down to the lowest position of their movement, where the supporting rails thereof turn a corner and pass along the inner top edges of the 40 tank. At this point the notched plates of the rapid conveyor chains will release the rods of the carriers, and by properly timing the operation, the slow conveyor chains will rise and pick up the rods, thus carrying them 45 along the tank slowly. In the tank the carriers will be bunched and move slowly, while in the rest of their journey they are spaced and moved fast. The builder can proportion his spacing and feeds to keep the tank conveyor chains full at all times.

The rapid conveyor chains then pass up from the tank level over the sprockets 9 and 10, and thence down to the sprockets 11. Just at the sprockets 11, the rails for the carriers turn up again, as at 5^b, and the slow conveyor chains pass down over their sprockets to return to the front of the machine again.

60 This relation of parts results in the rapid conveyor notched plates, when properly timed, picking up each carrier as it comes to the end of the tank, and by forcing its flanged wheels against the rail portions 5^b, causing the carriers to rise, and pass across the un-

loader device, the operation of which has been described.

Without an adequate spacing at the beginning and end of the process of pickling, it would be impractical to load and unload the carriers. Without a close spacing and slow movement in the tank, its extent would have to be far beyond practical limits in order to provide for sufficient pickling time.

70 The movement of the sheets slightly advanced from vertical position through the pickle liquor in the tank does not involve the moving parts of the machine, but merely the rods of the carriers, in action by the acid. It also provides an individual pickling of the 75 sheets by a constant current of the pickle liquor passing with maximum friction across the faces, and in around the backs of the sheets.

Having thus described our invention what 80 we claim as new and desire to secure by Letters Patent is:—

1. In a continuous pickling machine the combination with the tank of pickle liquor, 85 of a conveyor formed of carriers for metal articles, and means for moving said carriers, said means arranged to move the carriers relatively rapidly in spaced relation during the periods of insertion and withdrawal of material therefrom, and in relatively slow 90 closely spaced relation during the periods of immersion of the articles on the carriers in the tank.

2. In a continuous pickling machine the combination with the tank of pickle liquor, 95 of a conveyor formed of carriers for metal sheets, and means for moving said carriers, said means arranged to move the carriers relatively rapidly in spaced relation during the periods of insertion and withdrawal of the sheets therefrom, and in relatively slow, 100 closely spaced relation during the periods of immersion of the sheets on the carriers in the tank.

3. In a continuous pickling machine the combination with the tank of pickle liquor, 105 of a conveyor formed of carriers for metal sheets, and means for moving said carriers, said means arranged to move the carriers relatively rapidly in spaced relation during the periods of insertion and withdrawal of the sheets therefrom, and in relatively slow, 110 closely spaced relation during the periods of immersion of the sheets on the carriers in the tank, said carriers being formed of transverse members engaged by the moving means, and free to rock with relation to the same, and dependent arms for mounting sheets thereon,

115 said arms projecting at an angle such as to keep the sheets in a position other than vertical, thereby preventing the sheets from dropping away from the arms.

4. In a continuous pickling machine the combination with guides and traveling feeding means, of a carrier having members to

ride upon said guides and a cross member terminating in ends arranged for pivotal engagement by the feeding means, and an element for said carrier on which sheets of metal may be supported, said element comprising a portion against which the sides of metal sheets rest, and a portion to engage the lower edges of said sheets, said element shaped to hang diagonally under the influence of gravity whereby a sheet may rest against the side engaging portion thereof.

5 5. In a continuous pickling machine the combination with guides and a traveling feeding means, of a carrier comprising a cross member having means to engage the guides, and terminating in rodded ends for engagement by the traveling feeding means, a series of depending rods terminating in hooks which engage the edges of metal sheets that rest 10 against the sides, said rods connected in positive alignment to the cross member by means which throw the upper ends of the rods into a position behind the pivotal center of the rodded ends against the direction of movement of the carrier, for the purpose described.

15 6. In a pickling machine, guides for carriers passing through first a downward path, then a horizontal path along a tank of pickle liquor, and then in an upward path again, carriers having means to engage and follow said guides, and a conveyor arrangement formed of means for engaging said carriers, and forcing them against the vertical guides, and carrying them along the horizontal 20 guides, thus giving a downward, horizontal and upward movement to the carriers.

25 7. In a pickling machine, guides for carriers passing through first a downward path, then a horizontal path along a tank of pickle liquor, and then in an upward path again, carriers having means to engage and follow said guides, and a conveyor arrangement formed of means for engaging said carriers, and forcing them against the vertical guides, 30 and carrying them along the horizontal guides, thus giving a downward, horizontal and upward movement to the carriers, said conveyor arrangement formed of an independent element moving along the horizontal path, and elements carrying the carriers as 35 described down to the independent elements and lifting them away therefrom.

40 8. In a pickling machine, guides for carriers passing through first a downward path, then a horizontal path along a tank of pickle liquor, and then in an upward path again, carriers having means to engage and follow said guides, and a conveyor arrangement formed of means for engaging said carriers, and forcing them against the vertical guides, 45 and carrying them along the horizontal guides, thus giving a downward, horizontal and upward movement to the carriers, said conveyor arrangement formed of an independent element moving along the horizontal 50 path, and elements carrying the carriers as described down to the independent elements and lifting them away therefrom.

55 path, and elements carrying the carriers as described down to the independent elements and lifting them away therefrom, said last named elements moving more rapidly than the independent element.
